US0D1048067S

(12) **United States Design Patent** (10) **Patent No.:** **US D1,048,067 S**
(45) **Date of Patent:** **** Oct. 22, 2024**

(54) **DISPLAY SCREEN OR PORTION THEREOF
WITH GRAPHICAL USER INTERFACE**

(71) Applicant: **Google LLC**, Mountain View, CA (US)

(72) Inventors: **Christopher Kelley**, Orinda, CA (US); **Minsang Choi**, San Francisco, CA (US); **Pritam Singh Pebam**, San Francisco, CA (US); **Caroline Chilton**, Brooklyn, NY (US); **Carrie Linda Bisazza**, Santa Cruz, CA (US); **Matthew Roth**, Brooklyn, NY (US); **Sabrina Curry**, Emeryville, CA (US); **Natalie Michele Salaets**, Sunnyvale, CA (US); **Jongwon Yu**, Los Angeles, CA (US); **Belinda Zeng**, Cupertino, CA (US); **Harshit Kharbanda**, Pleasanton, CA (US); **Louis Wang**, San Francisco, CA (US); **Austin Wu**, Brooklyn, NY (US); **Nishant Ranka**, Sunnyvale, CA (US); **Morgane Magali Laure Sanglier**, San Francisco, CA (US)

(73) Assignee: **GOOGLE LLC**, Mountain View, CA (US)

(**) Term: **15 Years**

(21) Appl. No.: **29/866,692**

(22) Filed: **Sep. 23, 2022**

(51) LOC (14) Cl. **14-04**

(57) **CLAIM**

The ornamental design for a display screen or portion thereof with graphical user interface, as shown and described.

DESCRIPTION

The sole FIGURE is a front view of a display screen or portion thereof with graphical user interface showing the claimed design.

The outermost evenly spaced broken lines in the drawings show the electronic device, which is the environment of the design and forms no part of the claimed design. The dot-dash broken lines showing the display screen or portion thereof forms no part of the claimed design. The remaining broken

(Continued)

lines showing portions of the graphical user interface form no part of the claimed design.
